UNITED STATES PATENT OFFICE.

GEORGE MELNIK AND KONSTANTY SCHULTZ, OF PHILADELPHIA, PENNSYLVANIA.

SHIP-PROTECTOR.

1,244,627.

Specification of Letters Patent. Patented Oct. 30, 1917.

Application filed July 25, 1917. Serial No. 182,691.

To all whom it may concern:

Be it known that we, GEORGE MELNIK and KONSTANTY SCHULTZ, a subject of the Emperor of Austria and a citizen of Russia, residing at Philadelphia, in the county of Philadelphia and State of Pennsylvania, have invented certain new and useful Improvements in Ship-Protectors, of which the following is a specification.

10 This invention relates to certain new and useful improvements in a ship protector.

The primary object of the invention is the arrangement of a device adapted for protecting a ship against injury from torpedoes or other similar projectiles, the arrangement being such that the course of travel of an oncoming torpedo will be changed and the torpedo stopped in its travel before it reaches the ship and whereby any injury to

20 the ship is prevented.

A further object of the device is the provision of a protector for ships that possesses great strength but is readily carried by the ship without impeding its progress through

25 the water.

A still further object of the device is the provision of a suspending and holding means for torpedoes passing through the water toward a ship, the entire portion of 30 the ship of which is liable to be struck by torpedoes being protected thereby, while the device is of light weight, easily manufactured and may be readily attached to any form of ship or boat.

35 In the drawings forming a part of this application and in which like designating characters refer to corresponding parts throughout the several views,

Figure 1 is a side elevation of a ship provided with the present device.

Fig. 2 is an enlarged detail vertical sectional view through the same illustrating a torpedo approaching the boat and shown by dotted lines as retained by the device and

45 Fig. 3 is a perspective view of a portion of the device.

Referring more in detail to the drawings, a ship 10 is illustrated having a deck 11 wireless telegraph outfit 12, cannons 13 and funnels 14 and with the present device 50 arranged surrounding the hull 15 of the ship.

A plurality of substantially U-shaped brackets 16 are secured in spaced relations

around the hull 15 secured to the latter by 55 means of attaching plates 17 flatly engaging the outer surface of the hull. The outer closed or connecting portion 18 of the brackets 16 are downwardly inclined, it being understood that the brackets 16 are 60 arranged substantially at the water line of the hull 15 so that the normal surface of the water 19 will be intermediate the ends of the said oblique sides 18 of the brackets 16.

A plurality of spaced wires 20 are arranged through the bracket sides 18 adjacent the outer edges 21 thereof, thereby forming a wire fence construction entirely surrounding the hull 15. A similar arrangement of barbed wires 22 are arranged 70 through the bracket sides 18 in parallel relations adjacent the rear edges 23 thereof forming with the wires 20 a barrier or enclosure for the hull 15 at the water line thereof. The wires 20 and 22 are preferably secured to the brackets where they pass through the bracket sides 18 as at 29 although the wires may be loosely positioned therethrough if desired.

It will be seen that the barbed wires 22 80 are arranged in different horizontal planes with the unbarbed wires 20, this arrangement best shown in Fig. 2 of the drawing positions each pair of wires, consisting of one plain wire 20 and one barbed wire 22, in 85 a plane perpendicular and transverse to the oblique bracket 18. It will be evident that the pairs of plain and barbed wires will be arranged in substantially parallel planes which are oblique to the plane of the water 90 level 19.

Torpedoes such as 24 ordinarily travel beneath the water level 19 adjacent the surface thereof so that in the travel of the torpedo toward the hull 15, it will come in contact 95 with the wires 20 and upon partially passing between two of the same, the pointed end 25 of the torpedo will engage the adjacent barbed wire 22 which will deflect the torpedo downwardly as well as engaging 100 some of the barbs 26 with the torpedo, thereby stopping and retaining the torpedo within the wire entanglement carried by the brackets 16.

It will be understood that the wires 20 105 and 26 may be arranged around the hull of a boat in any desired manner such as by means of the brackets 16 it being only essen-

tial to the carrying out of the present objects that the wires be capable of deflecting the course of the oncoming torpedo 24 and of stopping and retaining the torpedo before it strikes the hull 15, it being understood that the oblique sides 18 of the brackets 16 may be positioned at any distance desired outwardly of the hull. The brackets 27 and 28 which are arranged at the opposite ends of the hull 15 may be slightly modified in form for accommodating the same to the curvature of the opposite ends of the hull, all of the brackets, however, arranging the plurality of wires 20 and 22 in spaced relations from the hull 15. This device offers very little resistance to the movement of the boat 10 through the water while the brackets 16, 27 and 28 may be readily mounted upon the hull of any boat and the wires 20 and 22 strung thereon as an encircling protector therefor.

Copies of this patent may be obtained for five cents each, by addressing the "Commissioner of Patents, Washington, D. C."

What we claim as new is:—

A protector for ships comprising in combination with the hull thereof, brackets secured to the hull in spaced relations and with one of said brackets arranged at each of the opposite ends of the hull, all of the said brackets having similarly inclined outwardly positioned oblique sides, plain wires extending between the said brackets adjacent the outer oblique sides and torpedo engaging barbed wires extending between said brackets adjacent the inner edges of the oblique sides thereof, the said barbed wires being individually arranged in slightly lower planes than that of the adjacent outwardly positioned plain wire.

In testimony whereof we affix our signatures.

GEORGE MELNIK.
KONSTANTY SCHULTZ.
